UNITED STATES PATENT OFFICE.

HENRY H. DEMING, OF CHICAGO, ILLINOIS, ASSIGNOR OF ONE-HALF TO AXEL J. JOHNSON,
OF CHICAGO, ILLINOIS.

HAME-FASTENER.

No. 923,955.

Specification of Letters Patent.

Patented June 8, 1909.

Application filed January 30, 1908. Serial No. 413,374.

To all whom it may concern:

Be it known that I, HENRY H. DEMING, a citizen of the United States, residing at Chicago, county of Cook, and State of Illinois, 5 have invented certain new and useful Improvements in Hame-Fasteners, of which the following is a specification.

My invention relates to hame fasteners, that is, to devices for connecting the lower 10 ends of the hames beneath the collar.

The object of my invention is to provide a hame fastener which may be readily and quickly operated to securely fasten the hames and which may be adjusted to secure 15 the hames as tightly or as loosely as desired.

A further object of my invention is to provide a hame fastener provided with a pivoted arm which may be used as a lever for tightening the hames, and so constructed 20 that the tension of the fastening will be shifted to the body portion of the device when secured.

A further object of my invention is to provide a device as mentioned so constructed 25 that the lever portion will automatically separate the parts as it is opened.

Other objects will appear hereinafter.

My invention will be more readily understood by reference to the accompanying 30 drawings forming a part of this specification and in which,

Figure 1 is a front elevation of the device illustrating the same in position upon the lower ends of the hames and in closed or 35 fastened position, Fig. 2 is a longitudinal section of the device in opened position, Fig. 3 is a detail sectional view in closed position, and Fig. 4 is a plan view.

Referring to the drawings, 1 indicates the 40 main portion or body of the fastening and 2 a hook formed thereon to engage a ring, 3 on the lower end of one of the hames, 4. This portion of the device is preferably formed of malleable iron and the hook, 2 is bent down 45 as shown in Fig. 1 to secure it to the ring, 3. At the opposite end of the device are a pair of lugs, 5 between which is pivoted an arm or lever, 6 upon the pin, 7. To the lower end of the opposite hame are secured a plurality of links, 8, 8' and 8''.

To fasten the hame the lever, 6 is passed through one of the links and then turned into the position shown in Fig. 1. This draws the hames toward each other and 50 throws the link upon the lugs, 5. This re-

lieves all strain upon the lever and its pivot pin when the device is in use. When either the link, 8 or 8' is used, the other link or links are turned back over the link or links in use, as shown in Fig. 3, the links being 60 hingedly connected. The arm or lever 6 is slightly curved and is provided or formed with a flat face or edge, 9 which lies substantially parallel with the body, 1 of the device when in closed position. When the 65 arm or lever is opened or thrown back, the face, 9 lifts the link off of the lug and disengages it from the body portion of the device. The face 9, by being in alinement with the lever portion 6, does not throw the link onto 70 the lever until the lever is past a position at right angles to the body and in position to permit the link to readily slip off.

10 indicates a spring secured to the back of the body, 1 and adapted to impinge against 75 the face 9 of the lever for holding it in closed position. This comprises the straight portion, 10' fixed to the back of the body, 1, a downwardly extending portion, 10'' and the offset portion, 10''', the latter of which rests 80 upon the lever, the body 1 being cut away between the lugs as at 11, for this purpose. The end of the lever and its edge opposite the face 9 is rounded as shown so that the spring will offer no resistance to the lever after having been partially thrown back.

12 indicates a lug formed upon the body portion between the hook, 2 and the lugs, 5 and against which the lever, 6 rests when in closed position, said lug thus forming a stop 90 for said lever.

Having described my invention what I claim as new and desire to secure by Letters Patent is:

1. A hame fastener comprising a link fixed 95 to the lower end of one of the hames and a fastening member secured to the lower end of the other hame, said member comprising a body portion having a hook formed at one end to secure the same to the hame and a 100 pair of lugs at the opposite end, and a slightly curved lever pivotally mounted between said lugs and provided with a straight face substantially in alinement with the arm of the lever said face being adapted to place said 105 link upon said lugs when swung to closed position and to remove the same therefrom when swung to open position, substantially as described.

2. A hame fastener comprising a link fixed 110

to the lower end of one of the hames and a fastening device secured to the lower end of the other hame and comprising a body portion having a hook formed at one end to secure the same to the hame and a pair of lugs at the opposite end, a lever pivotally mounted between said lugs and having a flat face adjacent to its pivotal point, said flat face being adapted to place said link upon said lugs when swung to closed position and to remove the same therefrom when swung to open position, said face lying substantially parallel with said body portion when in closed position, and a spring adapted to impinge against said face to hold the same in closed position, substantially as described.

3. A hame fastener comprising a link fixed to the lower end of one of the hames and a fastening member secured to the lower end of the other hame, said member comprising a body portion having a hook formed at one

end to secure the same to the hame and a pair of lugs at the opposite end, and a slightly curved lever pivotally mounted between said lugs and provided with a straight face substantially in alignment with the arm of the lever said face being adapted to place said link upon said lugs when swung to closed position and to remove the same therefrom when swung to open position, a spring adapted to impinge against the end of said face when the lever is in closed position, the end of said lever and the edge opposite said straight face being rounded, substantially as described.

In testimony whereof I have signed my name to this specification in the presence of two subscribing witnesses.

HENRY H. DEMING.
